UNITED STATES PATENT OFFICE.

JOHN HUNSINGER, JR., OF SECOR, ILLINOIS.

DESIGN FOR A WEDGE.

SPECIFICATION forming part of Design No. 31,975, dated December 12, 1899.

Application filed August 14, 1899. Serial No. 727,219. Term of patent 7 years.

To all whom it may concern:

Be it known that I, JOHN HUNSINGER, Jr., a citizen of the United States, residing at Secor, in the county of Woodford and State of Illinois, have invented and produced a new and useful Design for a Wedge, of which the following is a specification, reference being had to the accompanying drawings, which clearly illustrate my invention, and in which—
10 Figure 1 is a perspective view of a wedge constructed in accordance with my design, and Fig. 2 is a sectional view.

15 The essential feature of my design resides in the peculiar formation of the inclined sides of the wedge.

Referring to the drawings, A indicates one of the two flat faces of the wedge, said faces being slightly inclined, as illustrated.

B indicates the chiseled pointed edge of the wedge.

20 The sides C have a series of V-shaped grooves produced therein, thereby producing a series of recesses or indentations separated by a series of flat surfaces E.

Having thus fully described my invention, 25 what I claim as new, and desire to secure by Letters Patent of the United States, is—

The design for a wedge, substantially as herein shown and described.

JOHN HUNSINGER, JR.
